(57) **CLAIM**

The ornamental design for a display screen with animated graphical user interface, as shown and described.

DESCRIPTION

FIG. 1 is a front view of a first image in a sequence of a display screen with animated graphical user interface, showing a first embodiment of our new design;

FIG. 2 is a second image of the first embodiment;

FIG. 3 is a third image of the first embodiment;

FIG. 4 is a fourth image of the first embodiment;

FIG. 5 is a fifth image of the first embodiment;

FIG. 6 is a front view of a first image in a sequence of a display screen with animated graphical user interface, showing a second embodiment of our new design;

FIG. 7 is a second image of the second embodiment;

FIG. 8 is a third image of the second embodiment;

FIG. 9 is a fourth image of the second embodiment; and,

FIG. 10 is a fifth image of the second embodiment.

The appearance of a first embodiment of the image transitions sequentially between the images shown in the sequence of FIGS. 1 through 5, and the appearance of a second embodiment of the image transitions sequentially between the images shown in the sequence of FIGS. 6 through 10. The process or period in which one image transitions to another forms no part of the claimed design. The outermost broken lines illustrate an electronic device, which is the environment of the design, and forms no part of the claim. The remaining broken lines, including all text and icons, illustrate the display screen and portions of the graphical user interface that form no part of the claimed design.

1 Claim, 10 Drawing Sheets
